CLAIM

The ornamental design for a vehicle center bumper, as shown and described.

DESCRIPTION

FIG. 1 is a front perspective view of a vehicle center bumper showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken lines illustrated of a vehicle center bumper in FIG. 1 are for illustrative purposes only and form no part of the claim design.
